METHOD AND APPARATUS FOR CLEANING
GASESMorton I. Dorfan, Pittsburgh, Pa., assignor to
Blaw-Knox Company, Blawnox, Pa., a corpora-
tion of New Jersey

Application July 12, 1935, Serial No. 31,000

17 Claims. (CL 183—30)

My invention relates generally to the art of cleaning gases and, in particular, to the removal of suspended particles, either solid or liquid, from a stream of gas.

5 While various methods and numerous forms of apparatus have been proposed heretofore for the cleaning of gases, all these methods and devices with which I am familiar are objectionable for one reason or another, either their high first cost 10 or their relatively low efficiency of cleaning. I have invented a method and apparatus which represent a considerable improvement on the practice and apparatus of the prior art so far as I am familiar therewith.

15 In accordance with my invention, I subject gases to a mechanical cleaning operation and to a scrubbing or washing operation whereby all suspended particles are thoroughly removed from the gas and the latter may then be delivered to 20 any point of use, pure and uncontaminated by any suspended matter. The apparatus of my invention comprises generally a centrifugal separator and means for scrubbing the gas after passing through the separator.

25 A present preferred embodiment of the invention is illustrated in the accompanying drawings, although the latter are purely illustrative and not to be considered as limiting the invention in any wise. In the drawings:

30 Figure 1 is a central vertical sectional view taken through a gas-cleaning apparatus in accordance with my invention;

Figure 2 is a sectional view along the line II—II of Figure 1;

35 Figure 3 is a sectional view along the line III—III of Figure 1; the line I—I of Figure 3 indicates the plane on which the section of Figure 1 is taken;

Figure 4 is a sectional view taken along the line 40 IV—IV of Figure 1;

Figure 5 is a view similar to Figure 1 showing a modified form of the apparatus;

Figure 6 is a sectional view along the line 45 VI—VI of Figure 5; and

Figure 7 is a sectional view along the line VII—VII of Figure 5.

Referring now in detail to the drawings, the apparatus of my invention which I prefer to employ in the practice of the method thereof, 50 comprises a shell 10 preferably formed of sheet metal of suitable gauge. The shell 10 is preferably circular in cross section for maximum efficiency, although other shapes may be employed. An inlet 11 for the gas to be cleaned 55 communicates with the interior of the shell 10,

and is preferably disposed tangentially thereof, as shown in Figures 2 through 4. The shell 10 has a conical or funnel-shaped bottom 12.

An uptake 13 is positioned substantially centrally of the shell 10 and extends above and below 5 the inlet 11. A downwardly directed conical baffle 14 extends from the upper edge of the uptake 13 to the wall of the shell 10. The outer edge of the baffle 14 is recessed or notched as at 15 for a purpose which will appear presently. The uptake and the baffle are preferably secured together, as by welding, and both may be supported by welding the baffle at intervals to the 10 wall of the shell 10.

A scrubber bowl 16 is seated in the shell 10 15 above the uptake 13 and baffle 14 and is adapted to receive a supply of liquid through a port 17. The bowl has a drain pipe 18 controlled by a manually operable valve 19, the operating handle of the valve extending outwardly of the shell 10, 20 as indicated at 20. Conductor tubes 21 extend through the bowl 16 for the purpose of providing a passage for the gas to the space above the liquid pool maintained in the bowl.

An apron or funnel 22 is mounted in the shell 25 10 above the bowl 16. The spout of the funnel indicated at 23 extends downwardly through the bowl 16 and is provided at its lower end with a hood or distributor 24 of cone shape. Conductor tubes 25 extend through the collecting portion of 30 the apron or funnel 22 and downwardly below the upper ends of the conductor tubes 21.

A mist arrestor 26 is disposed in the shell 10 35 above the funnel 22. The arrestor may be composed of any suitable material, for example, a plurality of layers of woven wire or expanded metal mesh, or other material, which will efficiently serve the purpose of separating mist from the gas going therethrough. After traversing the mist arrestor 26, the gas flows through an outlet 40 27, whence it may be delivered to any point of use.

The operation of the apparatus shown in Figures 1 through 4 will now be described. The supply of liquid to the bowl 16 is regulated with regard to the rate of removal of liquid from the bowl, so that the surface level will approach the lower ends of the tubes 25. The gas to be cleaned is delivered to the shell 10 through the inlet 11. Because of the tangential arrangement of the inlet 11, the inflowing gas swirls 50 around the lower portion of the shell 10 and the conical bottom 12, with the result that any suspended particles are driven by centrifugal force toward the wall of the shell or its bottom. The lower portion of the shell and the conical bot- 55

tom thus constitute a so-called "vortex" or "cyclone" separator for removing suspended matter from the gas. After swirling around the lower portion of the shell 10 of the bottom 12, the main body of the gas flows upwardly through the uptake 13 and between the baffle 14 and the distributor hood 24. The gas is thus forced to traverse a circuitous path which tends further to remove any matter remaining suspended therein. The gas then flows upwardly through the tubes 21 to the space above the liquid pool maintained in the bowl 16. Because of the pressure on the gas being delivered through the inlet 11 or the vacuum maintained in the outlet 21, either or both of which may be employed, the gas flows from the space above the bowl 16 through the contractor tubes 25.

This arrangement of contactor tubes in a gas-cleaning apparatus is described and claimed in a copending application of Donald A. Sillers, Serial No. 587,684, filed January 20, 1932, and which has matured into Pat. No. 2,048,145, July 21, 1936, for Contact apparatus for liquid and gas. As explained in said application, the flow of gas across the surface of the liquid pool and through the tubes 25, causes intimate contact between the liquid and the gas whereby the gas is thoroughly scrubbed and any suspended matter remaining therein removed. The gas flowing upwardly through the tube 25 entrains a certain amount of the liquid in the form of droplets, which precipitate either directly upon the apron or funnel 22, or on the mist arrestor 26 from which the liquid drops onto the funnel. The precipitating drops further tend to sweep from the gas any suspended matter carried thereby.

The liquid collecting in the funnel 22 is delivered by the spout 23 thereof to the distributor hood 24. The latter is provided with guide vanes 28 which divide the downflowing-liquid and direct several streams thereof toward the recesses or notches 15 on the edge of the baffle 14. The liquid flows through the recesses or notches and spreads out substantially uniformly around the periphery of the bottom portion of the shell 10 and the conical bottom 12. The walls of these parts are thus continually washed by the streams of descending water which pick up and carry away any suspended matter removed by the cyclone separator. The liquid and suspended matter carried thereby collect at the lower end of the bottom 12 and are discharged through the outlet 29. An overflow outlet 30 is also provided so that if the outlet 29 becomes clogged with suspended matter removed from the gas, the liquid will escape at 30 and the bottom 12 can be cleaned by opening a clean-out valve 31.

In a modified form of apparatus shown in Figures 5 through 7, corresponding elements are indicated by the same reference numerals. This form of the invention differs from that already described in that the distributor hood 24 and the funnel 22 are omitted. Their function is performed by a conical cover 34 through which contactor tubes 35 project. The cover 34 has a depending cylindrical portion 36 extending downwardly to the outer edge of the baffle 14. The edge of the bowl 16 is spaced from the cylindrical portion 36 of the cover 34 to permit gas, after passing through the uptake 13, to flow around the edge of the bowl and over the surface of the liquid contained therein before flowing upwardly through the contactor tubes 35.

The droplets of liquid drawn through the tubes 35 by the outflowing gas fall on the cover

34 or collect on the arrestor 26, from which they subsequently fall onto the cover. The droplets received by the cover are directed toward the wall of the shell by reason of the conical shape of the cover and flow downwardly therealong to wash the walls of the shell and the bottom 12, and maintain these parts wet so that they readily pick up particles separated from the gas stream delivered to the cleaning apparatus. The advantage of the construction of Figures 5 through 7 is that fewer parts are required and the overall height of the apparatus is less than that of Figures 1 through 4.

It will be apparent from the foregoing description that the invention provides an effective method and apparatus for thoroughly cleaning gas and removing therefrom particles of suspended matter. The separation of the cleaning operation into two stages, viz., centrifugal or mechanical, and the hydraulic or scrubbing, is found to be particularly effective since particles that are not removed in one stage are unable to pass the second without removal from the gas. The field of application of the invention is almost unlimited and it may be used not only for cleaning or scrubbing but also for any other applications such as humidifying or air-conditioning systems where it is desired to obtain intimate contact of a gas and a liquid. The method is relatively simple to perform and the apparatus is easy to maintain. After the liquid supply is adjusted, practically no attention is required except occasionally to remove accumulated matter removed from the gas. The simplicity of the structure permits it to be manufactured at relatively low cost.

Although I have illustrated and described herein but one preferred embodiment of the invention and the method of its practice, it will be apparent that numerous changes in the method and apparatus disclosed may be made without departing from the spirit thereof or the scope of the appended claims.

I claim:

1. A gas-treating apparatus comprising a shell having a centrifugal separator in the lower portion thereof, a bowl above the separator for maintaining a pool of liquid, there being a relatively open space above said pool, an uptake from said separator, a baffle extending from the uptake toward the separator wall, tubes extending through the bottom of the bowl, gas discharge tubes extending almost to the liquid level in said bowl, a funnel for collecting liquid entrained by gas traversing the discharge tubes, and means for distributing the liquid collected by the funnel around said baffle for flow over the separator walls.

2. In a method of treating gas, the steps including subjecting particles entrained therewith to mechanical separation in a restricted zone, causing the gas to flow closely adjacent the surface of a pool of liquid, collecting the liquid thereby entrained with the gas and subsequently precipitated, and delivering the collected liquid to a said zone for washing away said particles.

3. In a method of treating gas, the steps including discharging a stream of gas into a cylindrical space tangentially thereof, causing sudden changes in the direction of flow of the gas, discharging the gas closely adjacent the surface of a liquid pool, collecting the liquid thereby entrained with the gas and subsequently precipitated, and delivering the collected liquid to the wall defining said space.

4. In a method of treating gas, the steps including discharging a stream of gas into a cylindrical space tangentially thereof, discharging the gas closely adjacent the surface of a liquid pool, collecting the liquid thereby entrained with the gas and subsequently precipitated, and delivering the collected liquid to the wall defining said space.
5. Gas cleaning apparatus comprising a shell, a bowl therein for holding liquid, a tube projecting downwardly from above the liquid to a point closely adjacent the surface thereof, means for conducting gas from below the bowl to a point above the surface of the liquid therein, means for collecting liquid entrained by the gas as it enters said tube, and means for delivering the collected liquid to the wall of the shell below said bowl.
6. Gas cleaning apparatus comprising a shell, a bowl therein for holding liquid, a tube projecting downwardly from above the liquid to a point closely adjacent the surface thereof, a tube extending upwardly through the bowl for admitting gas to the space above the liquid, a collecting funnel above the bowl, the spout of the funnel extending downwardly through the bowl, and a baffle below the bowl effective to deliver liquid from said spout to the wall of the shell.
7. Gas cleaning apparatus comprising a shell, a bowl therein for holding liquid, a tube projecting downwardly from above the liquid to a point closely adjacent the surface thereof, a gas inlet below the bowl, gas passages extending upwardly through the bowl, a collector for entrained liquid above the bowl, and a baffle between the bowl and the inlet for delivering liquid from the collector to the wall of the shell.
8. The apparatus defined by claim 7 characterized by an uptake in said shell extending from below said inlet toward said baffle.
9. Gas cleaning apparatus comprising a shell, a bowl therein for holding liquid, a cover over the bowl, a tube projecting through the cover to a point closely adjacent the surface of the liquid in the bowl, a gas inlet below the bowl, and a passage between the bowl and cover admitting gas to the space above the liquid, said cover being shaped to direct fluid precipitated from ascending gases onto the wall of said shell.
10. A gas-treating apparatus comprising a shell, a gas inlet communicating therewith, means for maintaining a liquid pool above the inlet, there being a relatively open space above the pool, a conduit for conducting the gas from below the pool to said space, a tube extending downwardly to a point closely adjacent the level of the pool for conducting the gas from said space after intimate contact with the liquid, and means on which liquid entrained by gas flowing through the last-mentioned tube descends, said means discharging said liquid onto the wall of the shell.
11. A gas-treating apparatus comprising a shell, a gas inlet communicating therewith, means for maintaining a liquid pool above the inlet, there being a relatively open space above the pool, a conduit for conducting the gas from below the pool to said space, a tube extending downwardly to a point closely adjacent the level of the pool for conducting the gas from said space after intimate contact with the liquid, means above said space on which liquid entrained by gas flowing through the last-mentioned tube descends, and means for delivering said liquid from said last-mentioned means to the wall of the shell.
12. A gas-treating apparatus comprising a shell, a gas inlet communicating therewith, means for maintaining a liquid pool above the inlet, there being a relatively open space above the pool, a conduit for conducting the gas from below the pool to said space, a tube extending downwardly to a point closely adjacent the level of the pool for conducting the gas from said space after intimate contact with the liquid, and means for collecting liquid entrained by the gas from said pool and delivering it to the wall of said shell.
13. A gas-treating apparatus comprising a shell having a centrifugal separator in the lower portion thereof, a bowl above the separator for maintaining a pool of liquid, there being a relatively open space above said pool, means for conducting gas from the separator to said space, a tube projecting closely adjacent the level of the liquid pool whereby gas may flow out of said space, and means on which liquid entrained by gas flowing through said tube descends, said means being effective for discharging such liquid onto the wall of the separator.
14. A gas-treating apparatus comprising a shell having a centrifugal separator in the lower portion thereof, a bowl above the separator for maintaining a pool of liquid, there being a relatively open space above said pool, means for conducting gas from the separator to said space, a tube projecting closely adjacent the level of the liquid pool whereby gas may flow out of said space, and means adjacent said tube adapted to receive liquid entrained by the gas flowing therethrough, and subsequently precipitated, and to deliver it to the wall of said separator.
15. A gas-treating apparatus comprising a shell having a centrifugal separator in the lower portion thereof, a bowl above the separator for maintaining a pool of liquid, there being a relatively open space above said pool, means for conducting gas from the separator to said space, and a tube projecting closely adjacent the level of the liquid pool whereby gas may flow out of said space, said conducting means including an uptake and a plurality of tubes extending through the bottom of the bowl.
16. Gas-cleaning apparatus comprising a mechanical separator effective to remove some at least of the particles carried by the gas, a scrubber above said separator, through which the gas flows, and means for delivering liquid entrained by the gas traversing the scrubber to said separator, to wash away the particles removed thereby.
17. A gas-treating apparatus comprising a shell, a gas inlet communicating therewith, means for maintaining a liquid pool above the inlet, there being a relatively open space above the pool, a conduit for conducting the gas from below the pool to said space, a tube extending downwardly to a point closely adjacent the level of the pool for conducting the gas from said space after intimate contact with the liquid, means overlying said pool for collecting any liquid entrained with the gas flowing through said last-mentioned tube, and means adapted to receive said liquid from said collecting means and deliver it to the wall of said shell.

MORTON I. DORFAN.
